Philip Davis Rice & Kennedy

UNITED STATES PATENT OFFICE.

JOSEPH JACOBS, OF NEW YORK, N. Y., ASSIGNOR TO THE LIVE LEATHER BELT COMPANY, A CORPORATION OF NEW YORK.

BODY-BELT.

1,282,586.

Specification of Letters Patent. Patented Oct. 22, 1918.

Original application filed June 30, 1915, Serial No. 37,161. Divided and this application filed August 2, 1916. Serial No. 112,646.

To all whom it may concern:

Be it known that I, JOSEPH JACOBS, a citizen of the United States, residing at New York city, county of Bronx, and State of New York, have invented certain new and useful Improvements in Body-Belts, fully described and represented in the following specification and the accompanying drawings, forming a part of the same.

10 The invention of this application, which is a division of an application filed by me June 30, 1915, Serial No. 37161, relates to improvements in elastic leather body belts, that is to say, composite belts for personal 15 wear consisting of or comprising superposed strips of leather and elastic material so combined that the belt will yieldingly encircle and engage the waist of the wearer.

In the accompanying drawing—

20 Figure 1 is a detail, in cross section, of a composite belt embodying the present invention;

25 Fig. 2 is a detail, in cross section, of the leather layer of the belt with a strip of elastic webbing thereon, before the edges of the leather layer are folded over the elastic webbing layer; and

30 Fig. 3 is a front view of the completed belt, in its contracted condition.

Referring to said drawing, the composite belt shown therein as embodying the present invention consists of two superposed layers A, B, united together, by means of cement and pressure as hereinafter described, so that the outer layer B will inclose and serve as a casing for the inner layer. For reasons which will be hereinafter stated the outer layer or casing B is leather, while the inner layer is elastic webbing. By "elastic webbing" I mean the material known commercially by that name and consisting of a textile fabric generally woven or knitted and containing india rubber strands or threads which are combined with suitable

45 strands of flexible fibrous material, such, for example, as wool, cotton, hemp, linen or the like. In practice it is advisable that elastic webbing selected for the manufacture of the belt be manufactured in a continuous 50 web of the proper width for the belt, since in this way is obtained a better union of the outer layer or casing A around the selvage edges of the elastic webbing.

The belt is made and the two layers A,

B thereof are united together in the following manner: Sides of leather are suitably slit into strips of a width about twice the width which the completed belt is to have plus a suitable amount to form an overlap. These leather strips are then skived or chamfered on both edges on one side, but on only one edge on the opposite side. This will be clear from Fig. 2. Generally that side of the leather strip which is to be inside the belt has its two edges skived or chamfered, while the side which is to be outside has only one edge chamfered.

The leather strips thus prepared are cemented together end to end to form a long web of leather, from which several belts may be cut. That side of the leather which is to be inside the belt is coated with a suitable adhesive composition, and most advantageously with a rubber cement, which is allowed to set or dry to a condition where it is tacky. The chamfered portion of the outside of the leather web is also provided with a coating of adhesive material such as above described. Where the outer surface of the leather web is colored, for example, black or tan, the adhesive applied to its chamfered edge portion is colored with suitable coloring material, so that the chamfered portion when coated with adhesive will have the same color as the remaining outside surface.

A long web of elastic webbing, of a width somewhat less than the width of the completed belt is stretched to the desired extent and laid against the central portion of the inside of the leather web. The two sides of the leather web are then folded over the elastic webbing, the sides of the leather overlapping each other to the extent of the skiving or chamfering of the edges, whereby a scarfed joint is formed longitudinally of the belt and along the central line of that side of the belt which is to be next the wearer.

The long composite web thus formed is now submitted to a heavy pressure, whereby the joined edges of leather are pressed into close contact with and firmly secured to each other, while at the same time the adhesive inside of the leather is firmly united to the elastic webbing.

After the leather and elastic webbing have been thus united, the tension on the

elastic webbing is released. Owing to the firm attachment of the elastic webbing to the inside of the leather in which the webbing is incased, the release of the tension on 5 the elastic webbing permits the latter to contract longitudinally and thereby contract the leather casing to the same extent. Because of its greater length over that of the elastic webbing, in the latter's contracted 10 condition, the leather strip will be crimped or corrugated transversely in contracting with the webbing, so that in a given length of the composite web there will be a greater length of leather than of elastic 15 webbing when the latter is contracted.

The product of these operations is a long web of composite elastic material comprising 20 a central flat core of elastic webbing entirely inclosed in and firmly combined with a casing of leather, the elasticity of 25 the composite web being due to the fact that owing to the crimps, corrugations or rugosities of the leather strip, in its contracted condition, the latter can be extended to the full extent to which the elastic webbing 30 itself may properly be stretched. Furthermore, the leather prevents the elastic webbing from being stretched to such an extent as would weaken such webbing. 35 The long composite web is now cut into body belt lengths and these lengths are finished in the usual way to provide a belt as, for example, by forming a tongue at one end and attaching a buckle and tongue socket or slide at the other end, as shown, for example, in Fig. 3.

Elastic webbing is selected as the inner member or layer of the belt, in combination 40 with leather as the outer or casing member, for the reason that with such combination of leather and elastic webbing it is possible to attain certain important results not attainable with other materials. One important result is the obtaining of the 45 requisite elasticity with the minimum amount of rubber, and another is the provision of a composite elastic belt having

wearing qualities equal to that of a leather belt of the same thickness. A still more important result, however, is the provision 50 of a composite elastic belt which, initially and throughout its use, will have a flat surface widthwise and have otherwise the appearance of an ordinary leather belt.

Leather has been selected as the outer 55 or casing member of the belt because it lends itself readily to perfect union with the elastic webbing for attaining these results. It may readily be softened, and, when of the proper thickness, will, after 60 the elastic webbing member is released and contracts, shorten with it and yet remain securely united to it. Owing to the adherence 65 of the leather casing to the elastic webbing, it is impossible to strain the elastic material beyond the desired limit predetermined in the manufacture of the belt, because the amount to which the elastic web may be stretched in the completed belt is limited by the extent to which the casing 70 may be stretched and this is determined by the amount of surplus material of the casing taken up in the crimp's, convolutions or corrugations formed in the leather as it contracts with the elastic webbing. 75

What I claim is:

1. A belt for body wear comprising a leather casing inclosing and cemented to a strip of elastic webbing, the length of leather in the casing being greater than that 80 of the elastic webbing, in the unstretched condition of the latter.

2. A belt for body wear comprising a leather casing inclosing and cemented to a strip of elastic webbing, with its edges overlapping and cemented together on the inner side of the belt, the length of leather in the casing being greater than that of the elastic webbing, in the unstretched condition of the latter. 85 90

In testimony whereof, I have hereunto set my hand.

JOSEPH JACOBS.
